TRANSISTOR RADIO

Shogo Imai, Osaka, Japan, assignor to Sharp Kabushiki
Kaisha, Osaka, Japan

Filed Dec. 28, 1970, Ser. No. 26,664

Term of patent 14 years

Int. Cl. D14—03

U.S. Cl. D56—4

Fig. 2

Fig. 1

Fig. 3

Fig. 8

Fig. 4

FIG. 1 is a front elevational view of a transistor radio, showing my new design;

FIG. 2 is a top plan view;

FIG. 3 is a bottom plan view;

FIG. 4 is a left side elevational view;

FIG. 5 is a right side elevational view;

FIG. 6 is a rear elevational view;

FIG. 7 is a left side, top and front perspective view; and

FIG. 8 is a cross-sectional view, partly in side elevation, taken along the line 8—8 in FIG. 7.

Portions of FIGS. 1, 2 and 7 are diagonally lined to indicate transparency.

I claim:

The ornamental design for a transistor radio, as shown and described.
